CONVERTIBLE VEHICULAR TOY

Gerard L. Lambert and Donald J. Maurer, Torrance,
Daniel H. Meggs, Hollywood Riviera, Stewart W.
Renner, Compton, and Herman C. Starner, Los Angeles,
Calif., assignors to Mattel, Inc., a corporation of
California

Filed Dec. 6, 1967, Ser. No. 9,652

Term of patent 14 years

U.S. Cl. D34—15

Int. Cl. D21—02

FIG. 5

FIG. 4

FIG. 3

Fig. 6

Fig. 7

FIG. 8

FIG. 9

FIG. 1 is a top plan view of a convertible vehicular toy with the wing and tail portions shown in an extended position showing our new design;

FIG. 2 is a bottom plan view of the design shown in FIG. 1;

FIG. 3 is a front elevational view of FIG. 1;

FIG. 4 is a rear elevational view of a convertible vehicular toy of our design with the wings shown in a closed position;

FIG. 5 is a front elevational view of FIG. 4;

FIG. 6 is a right side elevational view of FIG. 4;

FIG. 7 is a top plan view of FIG. 4;

FIG. 8 is a left side elevational view of FIG. 4; and

FIG. 9 is a bottom plan view of FIG. 4.

We claim:

The ornamental design for a convertible vehicular toy, as shown.
